CLAIM

The ornamental design for a shaving device, as shown and described.

DESCRIPTION

FIG. 1 is a front perspective view of a shaving device of the present invention showing my new design;

FIG. 2 is a front side elevation view thereof;

FIG. 3 is back side elevation view thereof;

FIG. 4 is a side elevation view thereof;

FIG. 5 is another side elevation view thereof;

FIG. 6 is a top plan view thereof; and,

FIG. 7 is a bottom plan view thereof.

In the drawings, the broken lines illustrate portions of the shaving device and form no part of the claimed design.

1 Claim, 5 Drawing Sheets
